ELEVATOR CONTROL SYSTEM

Edgar M. Bouton, Nutley, N. J., assignor to Westinghouse Electric Corporation, East Pittsburgh, Pa., a corporation of Pennsylvania

Application September 19, 1950, Serial No. 185,521

9 Claims. (Cl. 187—32)

1

The invention relates to motor control systems and more particularly to a system for controlling the speed of an elevator car during the retardation thereof prior to stopping.

In elevator systems, particularly those employing a single-speed alternating-current hoisting motor, slowdown or retardation and automatic stopping of the car level with a floor presents a problem because stopping is usually initiated at a fixed point in the hatchway with respect to the floor, and varying loading conditions of the car result in varying car speeds during the stopping operation. Accordingly, a system adjusted for a certain car load may result in over-shooting or stopping short of floor level with different car loads on different directions of car travel.

It is an object of the invention, therefore, to provide an improved control system for elevators in which the elevator car may be slowed and stopped accurately at floor level regardless of the load on the car.

It is a further object of the invention to provide a control system for a single-speed alternating-current motor in which the motor may be smoothly decelerated and stopped regardless of variations in loading conditions on the motor.

Another object of the invention is to provide an improved control system for an electric elevator motor which will bring the car to an accurate stop in accordance with the motor speed during slow-down regardless of the load on the car.

Other advantages will be apparent from the following description and accompanying drawings, in which:

Figure 1 is a schematic illustration of an elevator system in connection with which the present invention may be used;

Fig. 2 is a schematic diagram of a control circuit for the apparatus illustrated in Fig. 1;

Fig. 2A is a key-diagram which indicates the positions of the various relays and their contacts as shown in Fig. 2, and

Fig. 3 is a schematic view of an inductor relay used in connection with the invention.

Referring more particularly to Fig. 1, an elevator driving motor 2 may be of the single-speed alternating-current squirrel-cage type including an armature 3 and a three-phase Y-connected stator having windings *a*, *b* and *c*.

The shaft of armature 3 extends into a reduction gearing 4, which may be of a worm-gear type, the output of which drives a hoisting sheave 6, about which the hoisting rope or cable 8 extends, connecting a suitable counterweight 9 with the elevator car 10.

2

A service brake 12 includes a brake drum mounted on the motor shaft and has associated with it a brake shoe 11, which is spring-pressed into braking engagement by a spring 15. A brake winding C, to be energized when the elevator is in operation, is effective to release the brake against the force of spring 15. Normally, winding C will be deenergized during the stopping operation to permit the application of the brake shoe 11, which will stop the car and hold it in its stopped position.

The motor shaft is provided with a second brake H, the operation of which is variably controlled, as described later, by a winding B reacting on a piston 14 in a fluid system including a second piston 16 which operates to force a brake shoe 18 against its brake drum which is mounted on the motor shaft. Upon deenergization of winding B, the brake 18 will be released by spring 20, which was compressed when the brake shoe 18 was applied.

A tachometer generator TG is also mounted on the motor shaft to be driven in accordance with the motor speed, and includes separately excited field winding TGF.

An inductor relay 26 is mounted on the car 10 for movement therewith past a plurality of plates 22 and 23, of magnetic material, mounted in the hatchway at fixed points with respect to the various floors to be served. This type of relay is indicated more clearly in Fig. 4, and is of a well known type as shown, for example, in Santini Patent 2,298,174. Briefly, the relay includes a winding I and normally closed contacts DL and UL. The magnetic circuit of the relay is such that even though the winding I is energized, the contacts UL and DL will remain closed until the relay registers with a plate 22 or 23, at which point the magnetic circuit is completed by such plates to open the respective contacts DL or UL. For example, as shown in Fig. 4, the position of the relay indicates that the car is stopped accurately at floor level, at which point both plates 22 and 23 are effective to open the contacts UL and DL, respectively. However, upon movement of the relay with respect to the plates, sufficient to clear the relay from the magnetic influence of the plates, the contacts DL and UL will close. In other words, if the car and its relay move upward, as indicated by the arrow in Fig. 3, a relatively small movement will cause the contact DL to close, and the converse is true for contact UL for downward car movement.

The windings *a*, *b* and *c* of the hoisting motor 2 are energized from a three-phase alternating-current supply including leads L1, L2 and L3.

The energization of the motor is primarily controlled by the contacts M3, and the direction of rotation of the motor armature is controlled by the contacts U2 and D2 which are effective to reverse the connections to the motor windings *a* and *b*.

An iron core reactor 30 is connected in series with the lead L2 and is shunted by a circuit including normally open contact V1. The reactor 30 is of the saturable type, including a control winding A which is energized as hereinafter described.

The starting and stopping of the elevator car is controlled by the circuit shown in Fig. 2. Referring particularly to the lower portion of the diagram, the alternating-current leads L1 and L2 constitute the input to a full-wave rectifier 36, which may be a bridge of copper oxide rectifiers, and the output of the rectifier is connected to provide positive lead I(+) and a negative lead II(-), across which the control relay windings are connected.

There are many conventional types of elevator starting and stopping circuits which may be employed, but as a relatively simple example, it will be assumed that the car will be started and its stopping initiated by a car switch CS mounted in the elevator car. "Up" direction switch U and "down" direction switch D are provided to control the direction of rotation of the elevator motor 2 depending upon the direction of movement of the car switch handle, and the stopping of the car after the car switch handle has been centered will be controlled by the inductor relay 26 as it passes a plate 22 or a plate 23, depending upon the direction of car movement, to open respectively its contacts UL or DL.

As an assumed operation, with the elevator car standing at a floor and with its door open, if the operator desires to travel to a higher floor, he will first close the door. This will complete the circuit through the door interlocks and the winding of relay DR, assuming all the other door contacts of the installation are closed. Winding of relay DR will then close its contacts DR1 effecting a connection between the positive lead I+ to the movable contact of the car switch CS. When the operator moves the car switch handle in a counter-clockwise direction, for upward car movement, contact 38 will be engaged completing a circuit through the up direction switch U, closed contact D1 and the car running relay M.

Relay U will open its contact U1 in the circuit of the down direction switch D to prevent energization thereof, and will close its contacts U2 in the motor leads L1 and L2, which will permit appropriate rotation of the motor for the "up" direction.

Relay M will close its contacts M3 in the leads L1, L2 and L3 to complete the circuit for the motor and at the same time will close contacts M2 to energize the winding C of service brake 12, to release the brake, contacts U3 being already closed. The car will now move in the up direction, but at a relatively low speed because of the reactor 30 in lead L2 of the motor which imposes a relatively high impedance and results in a reduction of motor torque to substantially its single phase characteristics.

Further movement of the car switch handle in the counter-clockwise direction will bring the car up to normal speed. Contact 40 is engaged by the car switch to energize relay V, contacts DR2 having already been closed upon energization of

relay DR when the door interlock circuit was completed.

Relay V will close its contacts V1 in the shunt circuit around the reactor 30 which restores complete energization of the motor lead L2 and brings the motor up to synchronous speed. It will also open its contact V2, which controls the energization of the slow-down brake coil B as hereinafter described, and it will open contacts V3 to deenergize the coil I of the inductor relay. Contacts V4 will also be opened for a purpose to be described.

Assuming that the car is now traveling up at full speed, and a stop is intended, the operator 15 centers the car-switch CS thereby breaking the circuit to contacts 38 and 40. Opening the circuit at 40 deenergizes high-speed relay V, which results in (1) opening V1 which renders reactor 30 effective to reduce motor energization, (2) closes V3 to energize inductor winding I, and (3) closes V4 to complete a holding circuit for direction switch U and running relay M through closed inductor contacts UL.

Disregarding for the moment the control of 25 brake coil B and the bias coil A of the reactor 30, the car will proceed until a plate 22 adjacent to the desired landing becomes effective to open the contacts UL. Contacts UL when open will deenergize the up direction switch U which will open the contacts U3 in the circuit of coil C of the service brake 12 and permit application of the brake under the influence of its operating spring 16 to stop the car and hold it in stopped position. Contacts U2 in the motor winding leads will re-open and relay M being deenergized along with switch U, contacts M3 in the motor leads will open, completely disconnecting the motor from the source of supply.

It is contemplated that during slow-down the 40 brake H actuated by hydraulically applied pressure will be applied to assist in the slow-down operation by absorbing the stored energy in the system. The actuation of brake H is effected by coil B in a circuit shown in the upper portion of 45 Fig. 2. The circuit 44 includes series connected iron-core reactors 46 and 48, a full-wave rectifier bridge 50, and the contact V2 which closed when relay V dropped. The output of the bridge 50 includes windings 52 and 54, connected in opposition, for the reactors 48 and 46, respectively, and the brake coil B.

The impedance of reactors 46 and 48 is normally such that brake coil B would not be effectively energized, but such impedance may be reduced by the biasing coils 60 and 62 for these reactors, which coils are also connected in opposition. The energization of biasing coils 60 and 62 is controlled in the following manner.

At the point of initiating slow-down (when car 60 switch CS is centered), the tachometer generator TG is operating at substantially full speed, with its field TGF connected across the direct current leads I+ and II-. Assuming that at this time, with the car travelling up, the right hand 65 output terminal of TG is positive, contacts U4 being closed, the full output of TG is impressed on the biasing coils 60 and 62 through a circuit including a one-way rectifier 66, thereby decreasing the impedance of reactors 46 and 48 to a minimum, and permitting maximum energization of the brake coil B.

Coil B then operates, through pistons 14 and 16 and the fluid system therebetween, to apply brake shoe 18 to its drum to slow the elevator, 75 in addition to the retarding effect of reactor 30

in lead L2, to further overcome the inertia of the system.

As the elevator speed decreases, the output of TG also decreases until its voltage is balanced against an opposing voltage, or pattern voltage, from the voltage divider, the tap R being preferably so set that such balance occurs at 10% full speed of the elevator, but, of course, other speeds may be chosen as desired depending upon the operation required. When the two voltages are equal, no current will flow in the biasing coils 60 and 62, thereby rendering the impedance of reactors 46 and 48 of maximum value, and hence, a minimum energization of brake coil E. Accordingly, brake H initially has a maximum retarding effect which decreases as the elevator speed decreases to a minimum retarding action at the 10% speed point.

During the slow-down of the car to the 10% optimum, biasing coil A of reactor 30 has been substantially deenergized because the positive output of TG has been blocked by a rectifier or valve 68. Accordingly, coil A has had no effect on the high impedance of reactor 30, maintaining a slow-speed energization of the motor 2.

If the elevator speed tends to fall below the 10% optimum because of load on the car, the output of TG further decreases to a point where the voltage divider component will predominate, whereupon the direction of current flow through the armature of TG reverses. This will not affect the biasing coils 60 and 62 because of the rectifier 66, but it will energize the winding A of reactor 30 in accordance with the output of TG which will have the effect of reducing the impedance of reactor 30, causing an increase in motor torque to tend to bring the motor speed back to the 10% value. The motor will then arrive at a speed where the torque equals the load on the car, or at least be sufficient to maintain the desired landing speed without regard to the load on the car.

At a higher load, the speed of the car and hence the output of TG would further decrease, thereby increasing the energization of bias coil A, which further decreases the impedance of reactor 30, which in turn provides an increased motor torque to take care of the higher load.

With the apparatus and system disclosed, an automatic landing system for an elevator has been provided which is substantially independent of variations in loading conditions on the car over a rather wide range. By reason of the reactor 30 and its biasing winding, effective slow-down speed is readily obtained, and the stopping action is facilitated by the auxiliary hydraulic brake H which provides a smooth braking torque applied at a maximum force upon initiation of slow-down and gradually decreases as the car slows to a desired speed, the rate of decrease depending upon the speed of the car which, of course, is a function of the load on the car.

As previously indicated, although the elevator control system is shown as a relatively simple car-switch start and inductor-relay stop arrangement, quite obviously the invention may be applied to automatic push-button systems of various known types for passenger and freight elevators operating at speeds up to 250 or 300 feet per minute in which smooth retardation and accurate stops at floor level are desired factors.

I claim as my invention:

1. In an elevator system including an elevator car for serving a plurality of floors, a hoisting motor for said car having a brake for stopping the car at a floor and means for controlling said

motor to start said car and to initiate retardation thereof prior to stopping it at a floor; means for controlling automatically the retardation of said motor including means responsive to the initiation of retardation to decrease the energization of said motor to decrease the speed thereof, and means exerting a variable force in opposition to the torque of said motor for further decreasing the speed thereof to a desired predetermined speed, and means operable at a fixed point in the travel of the car with respect to said floor for deenergizing said motor and applying said brake to stop the car at said floor.

2. In an elevator system including an elevator car for serving a plurality of floors, a hoisting motor for said car having a brake for stopping the car at a floor and means for controlling said motor to start said car and to initiate retardation thereof prior to stopping it at a floor; means for controlling automatically the retardation of said motor including means responsive to the initiation of retardation to decrease the energization of said motor to decrease the speed thereof, means exerting a variable force in opposition to the torque of said motor for further decreasing the speed thereof to a predetermined desired speed, and means for increasing the energization of said motor in response to the speed thereof dropping below said predetermined speed prior to arrival of the car at a fixed point in the travel of said car.

3. In an elevator system including an elevator car for serving a plurality of floors, a hoisting motor for said car having a brake for stopping the car at a floor and means for controlling said motor to start said car and to initiate retardation thereof prior to stopping it at a floor; means for controlling automatically the retardation of said motor including means responsive to the initiation of retardation to decrease the energization of said motor to decrease the speed thereof, means exerting a variable force in opposition to the torque of said motor for further decreasing the speed thereof to a predetermined desired speed, and means for increasing the energization of said motor a variable amount in response to the speed thereof dropping to said predetermined speed prior to the arrival of the car at a fixed point in the travel of said car, said variable amount of increase in energization depending upon the difference between said speeds.

4. In an elevator system comprising an elevator car, an alternating current hoisting motor therefor having a brake to stop the motor and a control system for said motor to start the car and initiate retardation thereof prior to making a stop at a floor; means for automatically controlling the retardation of said car including means responsive to said initiation of retardation to increase the impedance of the energizing circuit of said motor to decrease the speed thereof, an electrically operated brake for said motor, and means responsive to said initiation of retardation to actuate said brake to exert a force on said motor proportional to the speed thereof to further decrease the speed of the motor until a desired predetermined low speed is attained, and means operable at a fixed point in the travel of the car with respect to said floor for deenergizing said motor and applying said brake to stop said car level with said floor.

5. In an elevator system comprising an elevator car, an alternating current hoisting motor therefor having a brake to stop the motor and a control system for said motor to start the car

and initiate retardation thereof prior to making a stop at a floor; means for automatically controlling the retardation of said car including means responsive to said initiation of retardation to increase the impedance of the energizing circuit of said motor to decrease the speed thereof, an electrically operated brake for said motor, and means responsive to said initiation of retardation to actuate said brake to exert a braking force on said motor proportional to the speed thereof, said last-named means including means responsive to the speed of said motor for generating a control voltage for affecting the degree of energization of said brake.

6. In an elevator system comprising an elevator car, an alternating current hoisting motor therefor having a brake to stop the motor and a control system for said motor to start the car and initiate retardation thereof prior to making a stop at a floor; means for automatically controlling the retardation of said car including means responsive to said initiation of retardation to increase the impedance of the energizing circuit of said motor to decrease the speed thereof, an electrically operated brake for said motor, means responsive to said initiation of retardation to actuate said brake to exert a force on said motor proportional to the speed thereof to further decrease the speed of the motor until a desired predetermined speed is attained, and means responsive to a speed below said predetermined low speed for decreasing the impedance of the energizing circuit of said motor by an amount proportional to the difference between said speeds.

7. In an elevator system including an elevator car and an alternating current induction motor therefor having an energizing circuit, means for decreasing the speed of said motor to a desired low speed substantially below synchronous speed including an electrically operated brake for the motor, a variable reactor for varying the impedance of said motor circuit, means for generating an electrical potential proportional to the speed of said motor, means for establishing a pattern potential corresponding to said desired low speed, and means responsive to a comparison of said potentials for varying the energization of said brake and for varying the impedance of said reactor to maintain said desired low speed.

8. In an elevator system including an elevator car and an alternating current hoisting motor having an energizing circuit, means for starting said motor, means for controlling the speed of said motor to bring the car substantially level with a floor comprising means for varying the impedance of the motor energizing circuit to vary the speed of the motor, an electrically operated brake for retarding said motor, and means for applying it with a force which is a function of the motor speed, means for generating an electrical potential proportional to the speed of said motor, means for establishing a pattern potential corresponding to a desired low speed of said car, means responsive to a comparison of said potentials for decreasing the value of said impedance when the speed of the motor falls below said pattern potential and for increasing the value of said impedance when the motor speed exceeds said pattern potential.

9. In an elevator system comprising an elevator car, a hoisting motor therefor having a brake to stop the motor and a control system for said motor to start the car and control the stopping thereof level with a selected floor; means for initiating the retardation of said car for stopping at such floor including means responsive thereto to decrease the energization of said motor to decrease the speed thereof, a second brake for said motor and means responsive to said initiation of retardation for actuating it to exert a braking force proportional to the speed of said motor to further decrease the speed thereof to a desired predetermined speed, means responsive to a difference between the actual motor speed and said desired speed for varying the energization of said motor to attain such desired speed, and means operable at a fixed point in the travel of said car to deenergize said motor and apply said first mentioned brake to stop the car at said floor.
